UNITED STATES PATENT OFFICE.

ROBERT J. VICTOR, OF HUDDSONDALE, PENNSYLVANIA.

APPARATUS FOR FORMING DENTAL PLATES, &c.

SPECIFICATION forming part of Letters Patent No. 243,819, dated July 5, 1881.

Application filed May 9, 1881. (No model.)

To all whom it may concern:

Be it known that I, ROBERT J. VICTOR, of Hudsondale, in the county of Carbon and State of Pennsylvania, have invented certain new and useful Improvements in Apparatus for Forming Dental Plates and for other purposes, of which the following is a specification.

My invention relates more especially to that class of apparatus used for making celluloid dental plates in which the flask is closed as the heat increases and the celluloid becomes plastic; but my improved apparatus is also applicable to cases in which the plate is formed of other material and where it is to be vulcanized.

The object of my invention is to automatically gradually close the flask as the temperature rises, and when the flask has been closed to automatically stop the supply of fuel to the lamp.

A further object of my invention is to maintain the desired temperature when it has once been reached until the flask is closed and the supply of fuel cut off, and where the article is being vulcanized to maintain a given temperature for any desired length of time.

My invention further consists in certain improvements whereby a large radiating-surface in the vulcanizing-chamber is obtained, waste of heat prevented, and the general operation of the apparatus improved.

The accompanying drawing is a vertical section through my improved apparatus.

The vulcanizing-chamber, which is circular in shape, is formed of a body, A, having a cap, B, screwed or otherwise secured thereto, and a double bottom consisting of the plates C C', which are separated by a ring or strip, e, and are firmly secured by a screw-cap, D. The bottom plates are further secured and braced by bolts c' c'.

A coil of strong copper tubing, E, is arranged within the chamber, and a steam-tight connection formed at e between the lower end of the tube and the space between the bottom plates, C C'.

The tubing is shown as coiled spirally within the vulcanizing-chamber, but it could obviously be otherwise disposed therein.

Near the top of the flask the tubing is carried out of the vulcanizer, and its end is flanged, so as to form a face-joint with the section of

tubing E', which is similarly flanged and screw-threaded, the two being secured together by a nut, e', in the usual manner.

The tubing E' is passed into the vulcanizing-chamber through the cap-plate B, coiled horizontally therein just under the cap-plate, and then carried out of the opposite side of the chamber at e'.

A cylinder, F, is shown as formed in one piece with the cap B, but it may, of course, be made separately and suitably secured thereto. Within this cylinder a hollow piston-head, G, fits snugly, the piston or stem g working through a suitable packing-nut, g', in the screw-cap f of the cylinder. There are openings g' in the upper end of the hollow piston-head, so that there is free communication between the interior thereof and the cylinder F.

A tubular bracket, H, with which the end e' of the tubing is connected, communicates with the interior of the cylinder F, near its upper end. This bracket is provided with a cup, h, for the reception of mercury, which acts as a governor for the apparatus, and the operation of which will presently be described.

The vulcanizing-chamber and the parts connected therewith, above described, are suspended in and rest upon a jacket, X, as shown in the drawings, which jacket is perforated at its base and top to support a free combustion at the lamp Y.

The lamp is fed by a supply-tube, y, having a stop-cock, y', which is operated by a lever, Z, extending to the upper part of the apparatus, where it is pivoted to a horizontal lever, J, which is pivoted to a piston or plunger, J', in the mercury-cup. The inner end, j, of the lever J rests in a hole, k, in the vertical plate-spring K, which is secured upon the top of the cylinder F. A collar, L, having a guide-notch, l, to control the position of the spring K, is adjustably secured upon the piston g by a set-screw.

There is a free steam-tight communication from the double bottom of the vulcanizing-chamber through the tubing, tubular bracket, the cylinder F, and hollow piston-head G, and around the mercury-cup h.

In order to economize fuel and heat and insure a prompt working of the apparatus, I form the body A, caps B and D, cylinder F, and bracket H of material of small conductivity, and it may also be desirable to form the

tubing outside of the vulcanizing-chamber of similar material. This may be wrought-iron or whatever else may be deemed suitable.

The bottom plates, C C', the hollow piston G, and the tubing within the chamber are preferably made of copper, which is of high conductivity, and consequently radiates a great amount of heat. The bottom plates are also preferably made of wrought-copper, on account of its strength.

By coiling the tubing within the vulcanizing-chamber a large heat-radiating surface is obtained, and by the construction shown substantially the same degree of heat is applied to the flask O at all points, and uniformly good work is insured.

The operation of the apparatus is as follows: A sufficient quantity of water is poured into the tube E to fill the space between the plates C C' and part of the coiled tubing, if found expedient. The flask having been placed in the vulcanizing-chamber, immediately under the piston-head G, the cap B is put in place, the joint e' of the pipes screwed up, the plunger J' placed in the mercury-cup h, and the end j of the lever J is caught in the opening k in the spring. The collar L is then adjusted so as to trip the spring and release the lever J at the proper moment. The steam generated by the heat of the lamp circulates through the tubing, the bracket H, (around the mercury-cup h,) the cylinder F, and the hollow piston-head G. The pressure of the steam in the hollow piston-head forces it down upon the flask with a gradually-increasing pressure, so that as the heat increases and the celluloid softens under its influence the flask is automatically gradually closed. The required temperature for the work to be done having been previously determined and the mercury-governor having been arranged for this temperature, when it is reached the expansion of the mercury lifts the plunger and lever J, which slightly raises the upright lever Z and partly closes the cock in the fuel-supply tube, thus preventing the work from becoming overheated. This temperature will be maintained by the governor until the flask is completely closed, when the collar I withdraws the spring K from the end of the lever J and allows the lever Z by its gravity to fall and completely shut off the supply of fuel from the lamp.

The amount of heat required can readily be regulated by the quantity of mercury in the cup h, as will be well understood, and by omitting the mercury in the cup the apparatus will work with a continuously-increasing heat until the flask is closed, the lever mechanism tripped, and the supply of fuel cut off.

When the apparatus is used for vulcanizing, the collar L is adjusted so that it will not move the spring, and the temperature having been determined, the governor will maintain it as long as may be desired, and the vulcanizing-flask will be kept firmly closed by the pressure of the piston-head.

By the construction above described I produce an apparatus of great strength and one possessing many important advantages over those heretofore in use. Thus in celluloid work the flask is automatically closed by the gradual pressure of the steam. The apparatus therefore requires no attention after it has once been started; and as the pressure is constantly applied with a gradually-increasing force there is no danger of the apparatus being strained, as is the case where the flask is closed by hand with a screw. Further than this, the work can be done more rapidly, as the pressure is constantly applied and the flask closed and the work completed at the earliest possible moment.

It is obvious that the details of construction of my improved apparatus may be varied in many ways by those skilled in the art without departing from the spirit of my invention. For instance, instead of making the vulcanizing-chamber with a double copper bottom, as herein described, it might be made with a single bottom of iron, and might have the radiating-tube coiled thereon within the chamber, and the generating-tube outside of the bottom and just over the lamp. In practice it will, no doubt, be desired to incase the heating or vulcanizing chamber in a non-conducting jacket.

I am aware that it is not new to maintain a given temperature in apparatus of this kind by means of the expansion of mercury by the heat of the apparatus, and I do not, therefore, broadly claim such subject-matter.

I claim as my invention—

1. The herein-described improvement in the art of manufacturing celluloid dental plates and other articles, which consists in closing the flask by the pressure of steam.

2. The herein-described improvement in the art of manufacturing celluloid dental plates and other articles, which consists in closing the flask by the pressure of the steam generated in the working of the apparatus.

3. The herein-described improvement in the art of manufacturing celluloid dental plates and other articles, which consists in automatically closing the flask and cutting off the fuel-supply when the flask is closed by the pressure of the steam generated in the working of the apparatus.

4. The vulcanizing or heating chamber herein described, constructed, in part, of wrought-iron or some other material of small conductivity, and having a double copper bottom, substantially as set forth.

5. The vulcanizing or heating chamber herein described, constructed, in part, of wrought-iron or some other material of small conductivity, in combination with a coil of copper tubing disposed therein, substantially as and for the purpose set forth.

6. The combination, substantially as herein set forth, of the body of the vulcanizing or heating chamber, the bottom plates, the separating-ring, and the screw-cap.

7. The combination, substantially as herein set forth, of the body of the vulcanizing or heating chamber, the bottom plates, the separating-ring, the screw-cap, and the bracing-screws connecting the bottom plates.

8. The combination, substantially as herein set forth, of the vulcanizing or heating chamber having the double bottom and the copper tubing disposed within the chamber and communicating with the space between the bottom plates.

9. The combination, substantially as herein set forth, of the vulcanizing or heating chamber, the tubing E, disposed within the chamber, the cap-plate of the vulcanizing-chamber, the tubing E', coiled thereunder, and the joint between the tubes outside of the vulcanizing-chamber.

10. The combination, substantially as herein set forth, of a vulcanizing or heating chamber, a piston-head moving in a cylinder or steam-tight vessel and extending into the chamber, and a steam-generating apparatus for heating the chamber which communicates with the cylinder in which the piston works.

11. The combination, substantially as herein described, of a vulcanizing or heating chamber, a hollow piston-head working in a steam-tight cylinder and extending into the chamber, and a heating and steam-generating apparatus communicating with the cylinder, for the purpose set forth.

12. The combination, substantially as herein set forth, of the heating or vulcanizing-chamber, the tubings disposed therein, the joint between the tubings outside of the chamber, the cylinder on the cap-plate of the chamber with which the tube E' communicates, and the hollow piston-head working within the cylinder.

13. The combination, substantially as herein set forth, of the lamp, the heating or vulcanizing chamber, the tubings disposed therein, the joint in the tubings, the cylinder, the piston-head therein, the tubular bracket, the mercury-governor, and the lever mechanism for partly stopping the supply of fuel to the lamp.

14. The combination, substantially as herein set forth, of the lamp, the heating or vulcanizing chamber, the tubings disposed therein and communicating with the mercury-governor, and the lever mechanism for partly stopping the supply of fuel to the lamp.

15. The combination, substantially as herein set forth, of the lamp, the heating or vulcanizing chamber, the tubings disposed therein, the cylinder and piston-head, the adjustable tripping-collar on the piston, the spring, and the lever mechanism for cutting off the supply of fuel to the lamp when the flask has been closed.

16. The combination, substantially as herein set forth, of the lamp, the heating or vulcanizing chamber, the steam generating and heating apparatus, the mercury-governor, the lever mechanism which controls the fuel-supply, and mechanism for closing the flask and tripping the lever mechanism to cut off the supply of fuel when the flask is closed.

In testimony whereof I have hereunto subscribed my name this 6th day of May, A. D. 70 1881.

ROBERT J. VICTOR.
